BATTING MACHINE

Earl R. Overman, Wabash, Ind.

Application July 21, 1947, Serial No 762,362

17 Claims. (Cl. 164—76)

1

The present invention relates to a batting machine, and more specifically to a machine intended primarily for the purpose of longitudinally slitting a stream of rock wool or the like, thereafter applying to one surface of each stream a sheet of adhesive-coated paper, thereafter compacting each strip, and thereafter transversely cutting the strips into predetermined lengths, the machine being so constructed as to perform all of these operations automatically, and being quite flexible as regards the widths of the strips formed and the lengths of the pieces cut therefrom.

The primary object of the present invention, then, is to provide a machine of the character described. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a perspective view of a complete machine constructed in accordance with my invention;

Fig. 2 is a transverse section thereof, the upper part of the figure being taken upon a plane near the delivery end of the machine and the lower part of the figure being taken upon a parallel plane near the input end of the machine;

Fig. 3 is a fragmental perspective view of a detail;

Fig. 4 is an enlarged fragmental sectional view of another detail;

Fig. 5 is a longitudinal section of the machine, upon a reduced scale;

Fig. 6 is a broken fragmental perspective view showing the means for adjusting the compacting unit;

Fig. 7 is a fragmental perspective view of one end of the machine;

Fig. 8 is a fragmental perspective view of the means for causing movement of the boom;

Fig. 9 is a fragmental perspective view of the boom-carried supplemental platform;

Fig. 10 is a fragmental perspective view of the means for transporting the flying knives;

Fig. 11 is an enlarged, broken perspective of means for mounting knives on a shaft; and

Fig. 12 is a wiring diagram.

Referring more particularly to the drawings, it will be seen that the machine of the present

2

invention comprises a frame including longitudinally extending bed members 20, 20 supported upon standards 21, 21 at one end and 22, 22 at the other end, as well as longitudinal frame members 23, 23 parallel with, and located above, the members 20. Journalled in suitable bearings supported on the frame, and extending transversely of the frame adjacent the input end thereof is a shaft 24 carrying a sprocket 25 (Fig. 2) driven by a chain 26 from a motor 27. It will be obvious that any other form of driving means may be substituted to drive the shaft 24.

The shaft 24 carries sprockets supporting one end of an endless conveyor 28 which, in the illustrated embodiment of the invention, comprises a pair of chains supporting a plurality of transversely extending metal bars upon the outer surfaces of which are mounted wooden slats; but the particular construction of the conveyor 28 does not form a part of the present invention. The opposite end of the conveyor is supported upon a shaft 29 (Fig. 1) suitably journalled in bearings mounted adjacent the output end of the frame.

Near the input end of the machine is mounted a transversely extending shaft 30, the ends of said shaft being supported in shoes 31 (Fig. 3) slidably guided within the inturned flanges of the uprights 21, 21. At least one of said uprights is formed, as shown in Fig. 1, with a vertically extending slot 32 through which said shaft 30 projects to carry, outboard, a V-pulley 33 driven by a belt 34 from a V-pulley 35 carried on the spindle of a motor 36 which motor, in turn, is mounted upon a platform 37. The platform 37 is supported upon a bar 38 (Fig. 3) whose opposite ends are likewise fixed to shoes 31. A transversely extending frame member 40 is perforated to receive slidably a pair of guide rods 41, each of which is threaded near its lower end for engagement with a nut 42 formed or welded upon the bar 38, and each such rod is provided at its upper end with a head 43 engageable with the frame member 40 to limit downward movement of the bar 38.

Journalled upon the uprights 21, 21, above the frame member 40, is a shaft 44 carrying a crank 45 upon which is mounted a ratchet wheel 46 with which cooperates a pawl 47 (Fig. 1). Two cables 48 are secured to the bar 38 and project through openings in the frame member 40 to be wrapped about the shaft 44, the ends of said cables being fixed to said shaft as at 49.

Obviously, the crank 45 may be rotated in a clockwise direction, as viewed in Fig. 1, to lift

the assembly including the shaft 30, motor 36, and bar 38, and the pawl and ratchet may be used to hold that assembly in any desired position of elevation. The rods 41 may be properly adjusted to limit downward movement of the assembly.

Any desired number of disc knives 50 may be mounted upon the shaft 30 in any desired spaced relation along the length of said shaft. Suitable means will be provided for holding each knife in a selected position of adjustment on the shaft, and one preferred form of holding means will be described hereinafter. A feeding platform is indicated in Fig. 1 at 51, said platform being suitably supported above the level of the upper run of the conveyor 28, and being provided with slots 52 corresponding to the positions of the knives 50. Each knife projects into a slot 52 so that, as a stream of mineral wool is fed along the platform 51 toward the conveyor 28, it will encounter the knives and will be supported above the lowermost edges of said knives, whereby the stream will be completely severed by each knife, although the knives will not contact the conveyor 28.

At a point spaced longitudinally beyond the knives just described, a pair of uprights 53 will be supported between the frame members 20 and 23 at each side of the frame, and a hollow roller 54 is journalled in suitable bearings supported by said uprights. Said roller is maintained at an elevated temperature by the substantially continuous injection thereinto of steam at a desired temperature. The means for supplying heat to the roller 54 is shown in detail in Fig. 4, wherein it is to be seen that one end of the roller is formed with an axial port 55 sealed by a gland 56 into the outer end of which is threaded a tube 57 passing through the bearing 58 and having its outer end journalled in an anti-friction bearing 59. Bearing 59 is supported in a housing 60 whose end is closed by a gland 61, and with which is associated a branched fitting 62 providing a chamber 63 communicating with a steam supply pipe 64. The pipe 57 establishes communication between the chamber 63 and the interior of the roller 54.

A small pipe 65 is threadedly supported in the fitting 62 with one end in communication with a passage 66 formed in said fitting and communicating with a drain pipe 67. Said pipe 65 projects through the pipe 57, out of contact therewith, and so into the roller 54, having its inner end turned downwardly, as at 68, and projecting into proximity to the lowermost portion of said roller.

Steam condensing within the roller 54 will collect, of course, at the bottom of said roller, in the manner indicated at 69; and the super-atmospheric pressure within said roller will tend to force liquid through the pipe 68, and so into and through the drain pipe 67. Since the end 68 of the pipe 65 is close to the lowermost portion of the roller, the liquid level within the roller is held always at a minimum.

Beyond the roller 54 there are journalled two shafts 70, extending transversely of the machine frame, and carrying a suitable number of spacing discs 71, suitably spaced along the lengths thereof, in the manner illustrated in Fig. 1. Rolls of specially treated paper 72 are supported upon said shafts 70 in the indicated manner, and preferably two additional shafts 73 are journalled between and below the shafts 70, substantially in the relation illustrated in Fig. 5, for support-

ing said paper rolls after the diameters of such rolls have been reduced substantially to their cores. Shafts 73 do not carry spacers like the disc 71, but are positioned near enough to said spacers on the shafts 70 so that the rolls are held in desired positions.

I prefer to use heavy kraft paper coated, on one surface, with heat-sensitive adhesive material of a character well known in the art to which the present invention pertains. The strand 74 of paper is led from each roll beneath the shaft 70 nearer the heating roll 54, and thence over and around the heating roll, with its uncoated side in contact with such roll. The adhesive material on the paper strand is rendered tacky by heat absorbed from the roll 54, and said strand is led thence into contact with the upper surface of the stream 75 of rock wool flowing through the machine, and beneath a compacting unit indicated generally by the reference numeral 76.

The unit 76 is so positioned, with relation to the conveyor 28, that it exerts a compacting pressure upon the stream of material flowing between 25 said unit and said conveyor. As is clearly illustrated in Figs. 6 and 7, the uprights 77 are formed with vertical slots 79 in which are journalled oppositely projecting trunnions 78. Shoes 82 carried by the side members 81 of the unit 76 are threadedly engaged by screw shafts 80 journalled in the frame members 23 and held against downward movement relative to said frame members by collars 83 adjustably fixed thereto. It will be obvious that rotation of the shafts 80 will result in elevation or depression of the unit 76. An endless conveyor 84, whose construction may be similar to that of the conveyor 28, is supported upon shafts 85 which carry sprockets over which run chains 86.

40 One of the shafts 85 carries an outboard sprocket over which runs a chain 87 passing about suitable idler sprockets and a sprocket carried on a shaft 88 journalled in the frame elements 23 and extending transversely of the frame. The shaft 88 is driven by a chain 89 from a shaft 90 driven, in turn, by a chain 91 from a sprocket 92 carried on the shaft 24. Thus, the conveyor 84 is driven at all times when the conveyor 28 is being driven.

50 A boom assembly is indicated generally by the reference numeral 93 (Fig. 1). Such assembly comprises a pair of parallel, transversely extending beams 94 which project laterally beyond the opposite sides of the frame. Intermediate its ends, the boom assembly carries a pair of brackets 95 (Figs. 2 and 10) each of which is supported upon a pair of wheels 96 adapted to run upon the inturned flanges of the frame members 23, 23. Preferably, the wheels 96 will be associated with the brackets 95 through vertically extending slots 97, each wheel axially carrying a bearing collar 98 (Fig. 2) against which engages a thrust pin 99 threadedly associated with the bracket 95 and provided with a lock nut 100.

60 65 Through the medium of the thrust pins 99, the elevation of the boom 93 relative to the main frame of the machine can be adjusted, to some extent.

The assembly whereby transportation of the boom 93 longitudinally of the machine may be effected is indicated generally by the reference numeral 101 and is illustrated in greatest detail in Fig. 8. A plate 102 spans the beams 94, adjacent the longitudinal median plane of the main frame, and supports two vertical, spaced plates

103 and 104 in which is journalled a shaft 105 carrying, outboard, a sprocket 106, and inboard, a wheel 108. A pair of pivoted brake shoes 109 and 110 is operatively associated with the wheel 108, and a hinged lever 111 engages the shoe 109 while a second hinged lever 112 engages the shoe 110. A tie-rod 113 is adjustably fixed to the lever 111 and projects freely through the lever 112, beyond which it is engaged by a rocker arm 114. The remote end of the rocker arm 114 is engaged by the plunger 115 of a solenoid 116. Upon inspection of Fig. 8, it will be clear that, when the solenoid 116 is energized to draw its plunger 115 downwardly, the arm 114 will rock about the line of engagement of its downturned end with the lever 112 to press inwardly against the upper end of said lever 112 and to pull upon the tie-rod 113. Thereby, the upper ends of the levers 111 and 112 are moved toward each other to press the shoes 109 and 110 against the periphery of the wheel 108 to hold said wheel, and consequently the shaft 105, against rotation.

A chain 117 passes over the sprocket 106 and under an idler sprocket 119, thence about a sprocket 118 on the shaft 88, thence over a sprocket 123 on a shaft 124, under an idler sprocket 122, and thence about a sprocket 120 on a shaft 121.

As has been explained, the shaft 88 is constantly driven (Fig. 7) during operation of the conveyor 28. Thus, during operation of the conveyor 28, the chain 117 will be constantly driven. So long as the solenoid 116 is deenergized the sprocket 106 and shaft 105 will rotate freely; but when the solenoid 116 is energized to cause the shoes 109 and 110 to grip the wheel 108, the sprocket 106 will be held against rotation, and the boom assembly will be carried bodily with the chain 117, in the direction of length of the main frame. The direction of rotation of the shaft 88 is such that, under these circumstances, the boom assembly will be carried toward the output end of the machine; and the driving ratios are such that the rate of travel of the boom will be identical with the rate of travel of the conveyor 28.

The shaft 121 is journalled (see Fig. 1) immediately at the output end of the main frame and is chain connected, at 125, to drive a counting unit 126.

The unit 126 is commercially available, embodies a switch, and is so constructed that, upon a predetermined number of revolutions of its input shaft, that switch will be momentarily closed, whereafter the unit will reopen the switch and begin instantly to count again, to close the switch again upon the same number of shaft revolutions. The mechanism is capable of being set to close the switch after any predetermined number of shaft revolutions between limits, for instance 12 revolutions and 999 revolutions. The details of construction of this unit form no part of the present invention, and therefore are not illustrated and described herein. Its function in the organization of the present invention will appear hereinafter.

The shaft 124 is to be seen in Figs. 1, 2 and 8. It projects to one end of the boom assembly, where it carries a sprocket over which runs a chain 127 driving a sprocket on one of a series of rollers 128 (Figs. 1, 2 and 9). Each of said rollers carries, inboard, a sprocket 129, and a chain 130 engages all of said sprockets. It will be seen that the rollers 128 will be driven at all times except when the solenoid 116 is ener-

gized. When said solenoid is energized, rotation of the shaft 124 stops, since relative movement between the chain 117 and the boom assembly 93, upon which the shaft 124 is journalled, is thereby arrested.

As is clearly to be seen in Fig. 5, the stream 75 of material being treated is carried over the rollers 128, being thereby lifted out of engagement, temporarily, with the conveyor 28. When the boom assembly 93 is stationary, the rollers 128 will be driven, and the proportioning of the parts is such as to drive those rollers at a peripheral speed corresponding to the lineal speed of the conveyor 28. When the boom assembly 15 moves longitudinally of the machine, upon energization of the solenoid 116, the rollers 128 will be held against rotation, but will be bodily moved with the boom assembly, at the lineal velocity of the conveyor 28.

20 Springs 131 are anchored, at one end, to the uprights 77. At their opposite ends, said springs carry pulleys 132 around which extend cables 133, each cable being anchored at one end, as at 134, to a frame member 23, and at its opposite end to the boom assembly 93. The boom assembly is moved toward the output end of the machine by the chain drive above described; but is returned toward the input end of the machine, upon deenergization of the solenoid 116, by the springs 131.

Supported upon the boom for longitudinal movement with respect thereto is a transverse cutter assembly indicated generally by the reference numeral 135, to be seen in Figs. 1 and 2, 35 and perhaps most fully illustrated in Fig. 10. Said assembly comprises a horizontal plate 136 extending beneath, and traversing, the two beams 94, and carrying side plates 137, 137 in each of which is journalled a pair of wheels 138, 138 running upon the outturned lower flanges of the beams 94. Depending from said plate 136 is a reversible, three-phase motor 139 whose spindle 140 preferably projects axially therefrom in opposite directions to a considerable extent. Disc knife blades 141 are adjustably mountable upon either or both ends of said spindle, and in Fig. 11 I have illustrated one preferred means for securing said blades upon said spindle. If desired, the device illustrated in detail in Fig. 11 50 may be used, also, for adjustably securing the knives 50 upon the shaft 30.

A collar 142 is radially split, as at 143, and one section thereof is notched, as at 144 to accommodate the head 145 of a screw 145' extending through a chordal bore in said one section and threadedly engaging in an aligned socket in the other section of the collar. Said collar is formed with a coaxial sleeve 146 which is likewise radially slotted, and which is receivable upon the spindle 140. When the two sections of the collar and sleeve are separated, by opening the slot 143, the collar and sleeve are loose on the spindle 140, and may be readily adjusted thereabout or therealong. When, however, the collar and sleeve have been moved to desired position, the screw 145' may be tightened to draw the two sections of the collar together to bind the same in adjusted position rigidly on the spindle.

The knife blade 141 or 50 is loosely received 70 upon the sleeve 146, whose outer surface is threaded for the reception of a disc 147. Said disc 147 is provided with diametrically oppositely positioned sockets 148 for engagement by a spanner wrench; and is transaxially deeply slotted, as at 149. Midway between the ends

of the periphery of the slot 149, there is provided in the outer section of the disc 147 a threaded opening 150 in which is adapted to be received a screw 151 whose length is such as to extend completely through the outer section of the disc, to traverse the slot 149, and to engage the outer face of the inner section of said disc. After the knife blade has been mounted upon the sleeve 146, the disc 147 is threaded onto the sleeve 146, and is turned up tightly into engagement with the knife blade to bind the same frictionally between the disc 142 and the disc 147. Now, the screw 151 is turned down, the effect of which is to spread the two sections of the disc 147, opening the slot 149, pressing the inner section of the disc 147 more firmly against the knife blade, and tending to spread the thread portions of the disc 147 against the engaged thread portions of the sleeve 146, whereby the disc 147 is rigidly frictionally locked to the sleeve 146.

A chain 152 has one end secured to one end of the plate 136 (Fig. 10), thence passes around a sprocket 153 (Fig. 1) journalled near one end of the boom 93, thence passes around another sprocket 154 (Fig. 2) journalled near the other end of the boom, and so returns to the opposite end of the plate 136, to which it is fixed. A chain 155 provides a driving connection between the sprocket 154 and the output shaft of a reduction gear unit 156 driven by a reversible three-phase motor 157. This assembly, of course, is carried upon the boom 93.

A selector switch 158, mounted adjacent the motor 157, controls the direction of rotation of said motor in a manner which will later appear, and includes an arm 159 (Figs. 1, 2 and 10) whose outer end carries a roller with which cooperates an actuating cam 160. Said cam includes an upper surface 161 so positioned that, when the switch arm 159 engages said surface and the motor 157 is energized, the assembly 135 will be driven toward the left, as viewed in Fig. 2. Said cam comprises also a lower surface 162 so positioned that, when the arm 159 is in engagement therewith and the motor 157 is energized, the assembly 135 will be driven toward the right, as viewed in Fig. 2. The two surfaces 161 and 162 are joined by an inclined surface 163 of such angularity as to permit the roller on the arm 159 to move therealong easily as the cam is shifted.

A long rod 164 is operatively connected to shift the cam 160 and is guided in bearings 165, 166 near the opposite ends of the boom. Pivots operatively associated therewith are an operating arm 166 swingably mounted at 167 near one end of the path of the assembly 135, and an operating arm 168 pivotally mounted at 169 near the opposite end of the path of said assembly 135. One side plate 170 of the assembly 135 carries a projecting finger 170 cooperable with the arms 166 and 168. It will be seen, from an inspection of Fig. 2, that when the cam 160 is in the position there illustrated, the end of the arm 166 is disposed out of the path of the finger 170, while the end of the arm 168 is disposed in the path of said finger. It will be obvious, further, that when the finger 170 engages the arm 168, said arm will be swung in a clockwise direction to shift the cam 160 into the position in which the arm 159 rests upon the surface 162; and that such movement of the arm 168 will shift that arm out of the path of the finger 170 and will concurrently shift the arm 166 into the return path of the finger 170.

I have shown a preferred, but not essential,

10
15

form of means for securing the two ends of the chain 152 to the assembly 135. As shown, a block 171 is fixedly mounted at one end of the plate 136, and a polygonal pin 172 extends slidably therethrough. A link of the chain 152 is pivoted to the pin 172; and a coiled spring 173 is sleeved on said pin, confined between the block 171 and a head on the inner end of the pin 172. This gives a resilient connection between the chain and the assembly 135, whereby to take up shock when the motor 157 is energized.

The arms 166 and 168 may be mounted upon adjustable carriages 174 (Fig. 10). As shown, each such carriage comprises an L-shaped plate whose foot carries one or more clamping bolts projecting through a slot 175 in the upper flange of a beam 94, and elongated in the direction of length of said beam. By adjustment of the carriages 174, of course, the point in the travel of the assembly 135 at which the cam 160 will be shifted, can be varied. Preferably, but not necessarily, a control box 176 may be mounted at one end of the frame, being connected to a source of power through a cable 177. As shown, a tube 178 carries suitable leads to the stations at which power is required. For instance, at a median point in the path of travel of the boom 93, a flexible cable 179 projects upwardly from the frame element 23 and supports wires leading to the motor 157, the control switch 158, and an automatic reel unit 180. Said reel will automatically pay out, and take in, a cable 181, leading to the motor 139, as the unit 135 travels back and forth across the boom 93.

Referring, now, to the wiring diagram, Fig. 12, it will be seen that I have indicated line wires 182, 183 and 184 extending from a source of power. The selector switch 158 comprises a switch arm 185 which is directly connected to the line wire 182. Said switch arm 185 is movable between contacts 186 and 187, being controlled, in the manner above described, by the arm 159.

One side of the secondary coil of a transformer 188 is connected by a wire 189 with one terminal of the switch embodied in the counting or measuring device 126. The other side of said coil is connected, by a wire 190, with one end of a relay coil 191, the opposite end of which is connected, by wire 192, with the other terminal of said switch embodied in the unit 126.

Switch arms 193 and 194 are arranged to be shifted to circuit-closing position upon energization of the relay 191. When in closed position, the arm 193 connects wire 195, leading from contact 186 of switch 158, with wire 196. When the switch arm 185 is in the illustrated position, and the switch arm 193 is moved to closed position, a circuit is established from line wire 182 through arm 185, contact 186, wire 195, arm 193, and wire 196 through the coil of relay 197, controlling bridging switch 198, and the coil of relay 199, to line wire 183. Thereby, the bridge 198 is closed to establish a holding circuit for the relays 197 and 199 from line wire 182 through switch arm 185, contact 186, wire 195, wire 203, bridge 198, and relay coils 197 and 199 to line wire 183.

Energization of the relay 199 closes bridge elements 200, 201 and 202.

As has been stated, the unit 126 closes its switch only momentarily, and when that switch reopens, the relay 191 is deenergized, whereby the switch arms 193 and 194 are promptly returned to circuit-opening positions.

Closure of the bridge elements 200, 201 and 202 establishes an energizing circuit for the motor 139

as follows: from line wire 182 through bridge 200, wire 204, wire 205, and wire 206, to one terminal of the three-phase reversible A. C. motor 139; from line wire 183 through bridge 201, wire 249 and wire 250 to the opposite terminal of said motor; and from line wire 184 through bridge 202, wire 209, wire 208, and wire 207 to the intermediate terminal of said motor. The motor will thus be energized to drive the blades 141 in the most advantageous direction for cutting as the assembly 135 moves from the position illustrated in Fig. 1 to the opposite end of the boom assembly 93.

Concurrently with energization of the motor 139, the solenoid 116 is energized through wires 210 and 211, connected, respectively, with wires 206 and 207, to actuate the brake 109, 110 to grip the chain 117 against movement relative to the boom. The boom begins, at once, to move toward the discharge end of the machine.

A switch 212 is mounted upon a frame member 23 near the normal position of the boom 93. Said switch is biased to closed position, but is movable to open position by movement of a control arm 213 (Fig. 10) in a clockwise direction. Said arm 213 carries, at its free end, a roller 214 adapted to be engaged, as the boom 93 approaches its normal position of rest, by a cam 215 carried on one of the brackets 95. When said cam is in engagement with said roller 214, the switch 212 will be held in open position. When the boom begins to move, in the manner above described, the cam 215 will be moved out of engagement with the arm 214, whereupon the switch 212 will be closed. Closure of said switch establishes a circuit from line wire 182 through bridge 200, wire 204, wire 205, wire 216, wire 217, wire 218, switch 212, and wire 219 to energize relay coil 220 and relay coil 222, said circuit extending through wires 221, 223, 224, 208 and 209 through bridge 202 to line wire 184. Energization of the coils 220 and 222 will close bridge elements 225, 226, 227 and 228. The bridge element 225 establishes a holding circuit for the coils 220 and 222, independent of the switch 212, but dependent upon the bridges 200 and 202 which, in turn, are dependent upon the selector switch 158. That holding circuit may be traced from line wire 182 through bridge 200, wire 204, wire 205, wire 216, wire 217, bridge 225, coil 220, wire 221, coil 222, wire 223, wire 224, wire 208, wire 209, and bridge 202 to line wire 184.

Closure of the bridges 226, 227 and 228 establishes an energizing circuit for the reversible, three-phase A. C. motor 157, to drive said motor in a direction to propel the assembly 135 toward the left, as viewed in Fig. 1. That circuit may be traced from line wire 182, through bridge 200, wire 204, wire 205, wire 216, bridge 228, and wire 229, to one terminal of said motor; from line wire 183 through bridge 201, wire 249, wire 230, bridge 226 and wire 231 to the opposite terminal of said motor; and from line wire 184 through bridge 202, wire 209, wire 208, wire 224, bridge 227, and wire 232 to the intermediate terminal of said motor. Concurrently, a circuit is established through wires 233 and 235, connected, respectively, to wires 232 and 231, to energize the relay coil controlling the automatic brake 234 operatively associated with the motor 157. The construction of this brake is well known and need not here be shown or described in detail. Suffice it to say that the brake is normally set and is released by energization of its controlling circuit, so that the rotor of motor 157 will be

promptly arrested upon deenergization of said motor.

It will be noted that there is a time lag, controlled by the switch 212, between energization of the motor 139 and energization of the motor 157. This time lag is provided in order to insure synchronization of the movement of the boom 93 with the movement of the stream of material 75 flowing through the machine, and to permit the knives 141, driven by the motor 139, to attain full cutting speed before they are moved into engagement with said stream.

As the boom 93 moves toward the discharge end of the machine and the assembly 135 moves transversely of the machine, the projection 170 will pass beneath the arm 166 without touching it and will ultimately engage the arm 168 to shift the same in a clockwise direction as viewed in Fig. 2. Such movement of the arm 168 will shift the rod 164 to move the cam 160 toward the left as viewed in Fig. 2, thereby positioning the surface 162 in supporting relation to the roller carried upon the switch arm 159. As the surface 163 begins to move past the roller on the arm 159, the switch arm 185 is moved out of engagement with the contact 186. Thus, the holding circuit through that switch arm for the relays 197 and 199 is broken, and the bridges 198, 200, 201 and 202 are dropped into circuit-opening positions. Thus, the energizing circuits for the motors 139 and 157 and for the solenoid 116 are broken. The chain 117 is free to move relative to the boom, the motors come to rest, and the springs 131 return the boom 93 to its position of rest nearer the input end of the machine. The assembly 135 is left, beyond the lateral limits of the conveyor 28, at the lefthand end of the boom, as viewed in Fig. 1. As the boom nears its position of rest, the cam 215 engages the roller 214 to open the switch 212.

It is to be noted that, as the boom 93 is returned by the springs 131 toward the input end of the machine, the rate at which the shaft 124 will be driven will depend not upon the absolute velocity of the chain 117, but upon the sum of that absolute velocity and the rate of travel of the boom toward the input end of the machine. Therefore, the rollers 128 will, during transit of the boom, be driven at a peripheral velocity corresponding to the relative velocity between the conveyor 28 and the boom 93, thereby compensating for the movement of the boom and of the rollers 128 in a direction opposite to the direction of movement of the stream 75 of material passing over said rollers.

Meantime, the unit 126 has been counting shaft rotations, thereby measuring the flow of material through the machine; and when the length of material for which said unit is set has again passed the boom position of rest, the switch embodied in the unit 126 will again be momentarily closed to energize the relay coil 191.

Since the roller on the arm 159 now rests on the cam surface 162, the switch arm 185 will be in engagement with the contact 187. Therefore, closure of the switch 194 will establish a circuit from line wire 182 through switch arm 185, contact 187, wire 236, switch arm 194, wire 237, relay 238, relay 239, wire 240, and wire 247 to line wire 183. Thereby, bridges 241, 242, 243, and 244 will be moved to circuit-closing positions. A holding circuit for the relays 238 and 239 will thereby be established from line wire 182 through switch arm 185, contact 187, wire 236, wire 245, bridge 241, relays 238 and 239, wire 240, and wire

247 to line wire 183, that circuit being independent of the switch 194 which reopens promptly, upon opening of the switch embodied in the unit 126.

Now, line wire 182 is connected, through wire 246, bridge 242, wire 205, and wire 206 to the same terminal of motor 139 to which it was previously connected; line wire 183 is connected, through wire 247, bridge 243, wire 208, and wire 207 to the intermediate terminal of the motor 139; and line wire 184 is connected by wire 248, bridge 244, wire 249 and wire 250 to the opposite terminal of the motor 139. Thereby, the motor 139 is energized to rotate in the opposite direction. Of course, the solenoid 116 is energized, as before, to initiate movement of the boom 93 toward the output end of the machine.

As the boom begins to move, the switch 212 is again closed, in the manner above described, to energize the relays 220 and 222 to establish the same holding circuit through the bridge 225 and to close the bridges 226, 227 and 228. This time, the line wire 182 is connected, through wire 246, bridge 242, wire 205, wire 216, bridge 228, and wire 229 to the same terminal of the motor 157 to which it was previously connected; but line wire 183 is connected to the intermediate terminal of said motor through wire 247, bridge 243, wire 208, wire 224, bridge 227 and wire 232; while line wire 184 is connected to the opposite terminal of said motor through wire 248, bridge 244, wire 249, wire 230, bridge 226 and wire 231. Thereby, the motor 157 is driven in the opposite direction to return the assembly 135 from the lefthand end of the boom 93 to the position illustrated in Fig. 11. In its travel from the lefthand end to the righthand end of the boom, the projection 170 will this time clear the arm 168, but will strike the arm 166 to return said arm 166 and the parts associated therewith to the positions illustrated in Fig. 2. Thereby, the switch arm 185 is returned to the position illustrated in Fig. 12, and all energizing circuits are broken.

I have shown two knives 141 mounted on the spindle 140. So long as sections having a length not greater than the overall length of the spindle 140, and not less than the axial dimension of the motor 139, are to be cut, two transverse cuts can be made simultaneously, upon each pass of the assembly 135, the knives 141 being adjustable toward and away from each other. But if longer or shorter lengths are to be cut, one of the knives 141 will be removed from the assembly, and a single cut will be made upon each pass.

I claim as my invention:

1. In a machine of the class described, conveyor means for passing a stream of material longitudinally through the machine, and means for transversely cutting such stream during passage thereof through the machine, comprising a boom extending transversely of the machine and laterally beyond both edges of said conveyor, a carriage supported on said boom for travel substantially from end to end thereof, a rotary knife supported on said carriage for rotation upon an axis parallel with the line of travel of such stream, means periodically operative to drive said boom in synchronism with such stream, means, operative during such boom travel, to drive said carriage from one extreme position to its opposite extreme position thereon, means for rotating said knife during travel of said carriage, a series of parallel rollers carried on said boom and arranged on axes disposed in a common plane immediately above said conveyor, said stream of

material being guided to flow over said rollers, and means for driving said rollers at a peripheral speed and in a direction corresponding to the lineal movement of said conveyor while said boom is at rest, and for arresting rotation of said rollers while said boom travels in synchronism with said conveyor.

2. In a machine of the class described, conveyor means for passing a stream of material longitudinally through the machine, and means for transversely cutting such stream during passage thereof through the machine, comprising a boom extending transversely of the machine and laterally beyond both edges of said conveyor, a carriage supported on said boom for travel substantially from end to end thereof, a rotary knife supported on said carriage for rotation upon an axis parallel with the line of travel of such stream, means periodically operative to drive said boom in synchronism with such stream, means, operative during such boom travel, to drive said carriage from one extreme position to its opposite extreme position thereon, means for rotating said knife during travel of said carriage, a series of parallel rollers carried on same boom and arranged on axes disposed in a common plane immediately above said conveyor, said stream of material being guided to flow over said rollers, and means for driving said rollers at a peripheral speed and in a direction corresponding to the relative lineal movement between said conveyor and said boom at all times.

3. The machine of claim 1 in which said knife projects between two adjacent rollers.

4. In a machine of the class described, conveyor means for passing a stream of material longitudinally through the machine, and means for transversely cutting such stream during passage thereof through the machine, comprising a boom extending transversely of the machine and laterally beyond both edges of said conveyor, a carriage supported on said boom for travel substantially from end to end thereof, a rotary knife supported on said carriage for rotation upon an axis parallel with the line of travel of such stream, an endless chain having a run extending parallel with the line of movement of said conveyor, means for driving said run continuously in synchronism with said conveyor, a sprocket loosely journaled on said boom upon an axis transverse to said run, said sprocket meshing with said run, and means for braking said sprocket against rotation.

5. In the machine of claim 4, a series of parallel rollers arranged on said boom on axes traversing the direction of movement of said conveyor and disposed in a common plane immediately above said conveyor to support a portion of said stream of material, a shaft journaled on said boom, a sprocket fixed to said shaft and meshing with said chain, and a drive train connecting said shaft to drive said rollers.

6. The machine of claim 4 in which said braking means includes electrically-actuated means operable, when energized, to brake said sprocket.

7. In a machine of the class described, conveyor means for passing a stream of material longitudinally through the machine, and means for transversely cutting such stream during passage thereof through the machine, comprising a boom extending transversely of the machine and laterally beyond both edges of said conveyor, a carriage supported on said boom for travel substantially from end to end thereof, a first electric

motor operatively connected to drive said carriage, a rotary knife supported on said carriage for rotation upon an axis parallel with the line of travel of such stream, a second electric motor operatively connected to drive said knife, an endless chain having a run extending parallel with the line of movement of said conveyor, means for driving said run continuously in synchronism with said conveyor, a sprocket loosely journaled on said boom upon an axis transverse to said run and meshing with said run, braking means for said sprocket, electrically-actuated means operable when energized, to actuate said braking means to arrest rotation of said sprocket, an energizing circuit for said second motor, and an energizing circuit for said electrically-actuated means connected in parallel with said motor-energizing circuit.

8. The machine of claim 7 including an energizing circuit for said first motor and means preventing closure of said last-named circuit until after said electrically-actuated means has been energized.

9. The machine of claim 7 including an energizing circuit for said first motor, a switch dominating said last-named circuit, and means for holding said last-named switch open during initial movement of said boom.

10. The machine of claim 7 in which said boom is caused to travel, when said sprocket is braked, from a position of rest to a position nearer the discharge end of the machine, said machine including an energizing circuit for said first motor, a switch dominating said last-named circuit, and means carried by said boom and cooperating with said switch, when said boom is in its position of rest, to hold said switch open.

11. The machine of claim 7 in which said boom is caused to travel, when said sprocket is braked, from a position of rest to a position nearer the discharge end of the machine, said machine including means carried by said carriage and operable, as said carriage approaches the limit of its travel, to break the energizing circuit for said electrically-actuated means, and spring means operable upon release of said braking means to return said boom to its position of rest.

12. The machine of claim 10 including means carried by said carriage and operable, as said carriage approaches the limit of its travel, to break the energizing circuit for said electrically-actuated means, and spring means operable upon release of said braking means to return said boom to its position of rest.

13. In a machine of the class described, conveyor means for passing a stream of material longitudinally through the machine, and means for transversely cutting such stream during passage thereof through the machine, comprising a boom extending transversely of the machine and laterally beyond both edges of the conveyor, a carriage supported on said boom for travel substantially from end to end thereof, a rotary knife supported on said carriage for rotation upon an axis parallel with the line of travel of such stream, means periodically operative to drive said boom in synchronism with such stream, a first reversible electric motor mounted on said boom and operatively connected to drive said carriage reversely along said boom, a second reversible electric motor mounted on said carriage and operatively connected to drive said knife reversely, forward energizing circuits for said motors, reverse energizing circuits for said motors, and a selector switch shiftable between opposite posi-

tions and effective to select, alternatively, the forward circuits for both motors or the reverse circuits for both motors.

14. The machine of claim 13 including an actuator for said selector switch and means operatively associated with said actuator and engageable by said carriage, as said carriage moves along said boom in either direction to reverse the position of said selector switch.

15. In a machine of the character described, a trackway, a carriage mounted on said trackway for travel thereon, a reversible electric motor operatively connected to drive said carriage in either direction on said trackway, a forward energizing circuit for said motor, a reverse energizing circuit for said motor, a selector switch shiftable between opposite positions and effective to select, alternatively, said forward circuit or said reverse circuit, an elongated element disposed adjacent said trackway and shiftable oppositely longitudinally thereof, a lever pivotally mounted adjacent one end of the path of said carriage, and operatively connected to move with said element, a second lever pivotally mounted adjacent the other end of said path and operatively connected to move with said element, said element being operatively associated with said switch to shift the latter oppositely between its opposite positions upon opposite movements of said element, and means on said carriage and engageable with one of said levers, as said carriage nears an end of its path, to shift said element, thereby reversing the position of said switch, moving said one lever out of the path of said means, and moving the other lever into the returning path of said means.

16. In the machine of claim 15, a rotary knife journaled on said carriage, a second reversible electric motor mounted on said carriage and operatively connected to drive said knife, a forward energizing circuit for said second motor, and a reverse energizing circuit for said second motor, said switch being connected to select the forward energizing circuits for said motors concurrently and to select the reverse energizing circuits for said motors concurrently.

17. The organization of claim 15 in which said switch is provided with an operating arm and said elongated means is connected to a cam, said cam being shiftable with said element and providing two surfaces, located in separate planes and joined by an inclined surface, said two surfaces being alternatively associable with said arm to shift said switch between its opposite positions.
